UNITED STATES PATENT OFFICE.

BERT A. OVENSHIRE, OF CAMPBELL, PENNSYLVANIA.

SAFETY DEVICE FOR SIGNAL-OPERATORS.

No. 834,845.

Specification of Letters Patent.

Patented Oct. 30, 1906.

Application filed March 16, 1906. Serial No. 306,479.

To all whom it may concern:

Be it known that I, BERT A. OVENSHIRE, a citizen of the United States, residing at Campbell, in the county of Lycoming and State of Pennsylvania, have invented certain new and useful Improvements in Safety Devices for Signal-Operators, of which the following is a specification.

In connection with block-signal systems for the handling of railway-trains it is customary to employ in the operator's tower a series of handles or levers designed to vary the lights, semaphores, targets, or similar display-signals along the track, according to the telegraphic orders received by the operator in the tower, to indicate to an approaching train whether the block be occupied or not by another train or, in short, whether the engine-driver of the oncoming train shall pass into the next block with a clear track ahead or to proceed with caution expecting a train in the said block. To convey these orders to the engine-driver in the almost universally-recognized custom, a red and a green signal are employed, both being preferably manipulated by hand-levers in the operator's tower and said levers being preferably arranged side by side, so that when "red" and "green" levers are thrown over from the danger-point a clear track will be indicated and if only red lever be thrown over from the danger-point it will be indicated that the engine-driver should proceed with caution, expecting a train in the next block. When, however, a station or block-tower has orders for a train, these levers must not be pulled from red position for any train until these orders are executed. Under the present conditions, as I am aware of them, no means have heretofore been provided whereby to prevent the lever from being pulled from the danger position, except the vigilance and carefulness of the operator himself; and the object of my invention is to provide an improved means which will not only prevent the throwing of the levers from the danger position without sharply bringing to the attention of the operator the fact that he is changing the signals, but which will also serve as a means for calling his attention to the order which he has received for the expected trains when he proceeds to adjust the signals in any manner.

With this object in view the invention consists, essentially, of an improved locking device designed to slip over the handle ends of

the signal-levers into contact with the handle portions of the locking-detents and in such position that it will be impossible to press such handle portions of the detents toward the levers to unlock the latter until my improved device shall have been removed, the said locking device at the same time serving as a tablet or board for the display of the various train-orders, so that the latter will be called to the operator's attention before he removes the locking device preparatory to throwing the levers for the change of signals.

For a full description of the invention and the merits thereof and also to acquire a knowledge of the details of construction of the means for effecting the result reference is to be had to the following description and accompanying drawings, in which—

Figure 1 is a perspective view illustrating my invention applied. Fig. 2 is a vertical sectional view. Fig. 3 is a horizontal section. Fig. 4 is a detail perspective view of the hood constituting the locking device of my invention, said hood being shown detached from the tablet or board designed for the display of the various train-orders.

Corresponding and like parts are referred to in the following description and indicated in all the views of the drawings by the same reference characters.

Referring to the drawings, the numeral 1 designates the ordinary quadrant, and 2 designates the levers for operating the signals in any desired or customary manner, said levers being provided with handle portions 3 and with detents 4, designed to hold the levers locked in their different positions in the slots of the quadrant in the well-known manner. The detents 4 are in the present instance provided with the usual hand pressing portions 5, so that the operator may readily disengage the detents from the quadrant by pressing on the portion 5 while his hands rest upon the handle portion 3 of the lever. All of the above-named parts may be of any desired form and construction. In connection with this signal-operating means my invention comprises a locking device, which in the present instance is in the form of a hood 6, designed to be inserted downward over the operating ends or handle portions 3 of the levers 2 and provided with a rearwardly-extending flange 7 at its lower end designed to contact with the inner sides of the handle portions 5 of the detents 4 to prevent the movement thereof. The hood 6

is preferably provided at one side with a downward extension 8, which bears against one side of the levers to rigidly support the hood in place. In order that the hood may 5 serve as a convenient support for train-orders, as intimated at the outset of the description, it has secured to its front face a tablet or board 9, which may be provided on its outer surface with a series of prongs or hooks 10, 10 preferably arranged in diagonally-extending series, with their points facing upwardly in convenient position to be pierced, and thereby support train-orders, as shown at 11.

From the foregoing description, in connection with the accompanying drawings, it will 15 be noted that the hood 6 not only constitutes a wedge between the handle portions of the levers 2 and the handle portions 5 of the detents 4, so that it will prevent the release of 20 the levers, but it also constitutes, in connection with the tablet 9, a convenient means for displaying train-orders in such a position that the operator will have his attention called thereto before he can change the signals, as 25 it will be necessary for him to grasp the tablet or hood and detach the same from the levers before he can manipulate the levers to vary the signals. Hence it will be practically impossible for him to overlook any 30 train-orders or to throw the signal-levers from the danger-point indicated in Fig. 1 without having his attention called to the orders, and I therefore believe that many serious accidents may be averted by the use 35 of my safety device.

Having thus described the invention, what is claimed as new is—

1. A device of the character described, comprising a hood designed to be inserted 40 over the handle ends of signal-operating levers and arranged to wedge against the handle portions of the detents thereof, as and for the purpose set forth.

2. The combination with signal-operating levers and their hand-released detents, of detachable means designed to wedge between the handle portions of the levers and said detents, as and for the purpose set forth. 45

3. A device of the character described, comprising a hood designed to be inserted 50 over the handle ends of signal-operating levers and provided at its lower end with a flange designed to engage the hand pressing portion of the detents of said levers, for the purpose specified. 55

4. A device of the character described comprising a locking device for the detents of signal-operating levers, and a display-tablet for train-orders, supported by said locking device. 60

5. A device of the character described comprising a hood designed to be inserted over the handle ends of signal-operating levers and arranged to lock the detents thereof, and a tablet supported by said hood for 65 the purpose specified.

6. A device of the character described comprising a hood designed to be inserted over the handle ends of signal-operating levers and a tablet secured to said hood and 70 provided with hooks by which train-orders may be attached to said tablet in display position.

7. A device of the character described comprising a hood designed to be inserted 75 over the handle ends of signal-operating levers and provided with a diagonally-extending series of hooks for the purpose specified.

In testimony whereof I affix my signature 80 in presence of two witnesses.
